UNITED STATES PATENT OFFICE.

ANDREW L. RIKER, OF BRIDGEPORT, CONNECTICUT, ASSIGNOR TO THE "LOCOMOBILE COMPANY OF AMERICA, OF NEW YORK, N. Y., A CORPORATION OF WEST VIRGINIA.

INTERNAL COMBUSTION ENGINE.

1,268,623.

Specification of Letters Patent. Patented June 4, 1918.

Application filed March 28, 1910. Serial No. 551,844.

To all whom it may concern:

Be it known that I, ANDREW L. RIKER, a citizen of the United States, and a resident of Bridgeport, in the county of Fairfield 5 and State of Connecticut, have invented an Improvement in Internal Combustion Engines, (Case B), of which the following description, in connection with the accompanying drawings, is a specification, like letters 10 on the drawings representing like parts.

This invention relates to internal combustion engines, and consists in improvements both in the operation and construction thereof.

15 The invention will be best understood by reference to the following description when taken in connection with the accompanying illustration of one specific embodiment thereof, the scope of the invention being particularly pointed out in the appended claims.

In the drawings.

Figure 1 is a vertical, sectional elevation taken through a cylinder and the crank case of a multiple cylinder engine embodying one 25 form of the invention; and

Fig. 2 is a similar view of a slightly modified form of the invention.

Referring to the drawings and to that embodiment of my invention therein selected 30 for illustrative purposes, I have there shown the construction of one cylinder of a four-cylinder engine. This engine is illustrated as of a size and form suitable for automobile use, but it is thus shown for illustrative 35 purposes only, the invention being independent of the form, type or size of engine employed, and also independent of its utilization in an engine having either a single cylinder or a plurality of cylinders.

40 The engine is shown as supported upon the crank casing 1 in which is suitably journaled the engine crank shaft 2 having a crank and crank pin connection 3 to the piston rod 4 which latter has a trunk connection 45 to the cylindrical piston 5.

The piston is adapted to reciprocate within a suitable and preferably upright cylinder 6, the latter being herein shown as surrounded by the usual water jacket 7 and 50 having its end closed by an appropriately shaped head 8 into which latter is fitted a plug 9 forming part of the ignition apparatus. The latter may be of any suitable nature, but herein is of the jump-spark type

having electric connections to a suitable high potential source of current.

While my invention as to certain of its features is not limited to the type of engine employed, the particular form of engine shown is constructed to operate upon the Otto or four-cycle principle, and presents features of novelty in its mode of operation, particularly in respect to the introduction of the fuel charged air into the working cylinder of the engine and the discharge of the spent gases therefrom. Designed to cooperate particularly with this type of engine, but having also useful application to engines which are functionally and constructionally quite different from the one described, there are provided various features of novelty to be hereinafter more particularly pointed out.

Referring first to Fig. 1, the admission of the fuel mixture to the cylinder and the exhaust of the spent gases therefrom are controlled by independent valves preferably operated by suitable connections from the crank shaft 2.

The admission pipe for the fuel mixture is indicated at 10 and is preferably at one side of the cylinder 6 and communicates with a passage 11 formed in a laterally projecting portion 12 of the said cylinder.

Extending from or forming a continuation 85 of the passage 11 is a transverse passage 13 extending to the interior of the cylinder 6 preferably adjacent the head 8 thereof and herein shown as communicating therewith between said head and the piston 90 when at its outward limit of movement. The said laterally projecting portion of the cylinder 6 is cored or otherwise formed to provide a preferably cylindrical chamber 14 for a plunger like admission valve 15. The chamber within which said valve is adapted to move and preferably to slide is shown as extending from the upper face of the head to a transverse web 16, through which passes a valve rod 19 threaded at its upper end to 100 said valve and preferably composed of two parts 19, 19' adjustably connected by a right and left threaded sleeve 20. While any suitable means may be employed to reciprocate said rod and valve, I preferably provide 105 means positively to move the same in both directions of reciprocation. To that end I have represented a shaft 21 suitably driven

from the crank shaft 2 or other suitable part, as by means of gearing, as indicated in dotted lines in said Fig. 1, and preferably in the ratio of two to one. Upon the shaft 5 21 is fast an eccentric 38 having an eccentric strap 39 pivoted to a lever 40 mounted upon a suitable part of the frame and connected at its outer end by a link 41 to the valve rod 19. Any suitable connection may be 10 employed between the eccentric and said valve rod, but preferably I provide means such as the lever 40 to reduce the length of stroke of the valve rod 19 and valve 15. In the construction shown, the valve is positively moved in both directions of reciprocation.

The upper end of the valve chamber is closed by a plug 22 threaded thereinto, and the said valve is provided with a transverse 20 port 23 adapted, when the valve is lifted, to place the passage 11 in communication with the interior of the cylinder for the admission of the fuel mixture thereto.

While any suitable type and arrangement 25 of exhaust valve may be provided, I have herein represented a valve 24, similar it may be to the admission valve 15. That is to say, the said valve is adapted to be reciprocated in a plunger like manner within a preferably cylindrical chamber 25 formed in a laterally projecting portion of the cylinder and herein shown as diametrically opposite the admission valve 15. The upper end of the valve chamber is represented as closed 30 by a threaded plug 26 and the said valve is provided with a valve rod 27 suitably reciprocated and as herein shown by substantially the means indicated for reciprocating the valve 15. That is to say, the valve rod 40 27 has adjustably connected thereto by a right and left threaded sleeve 28 a rod 27'. Upon a shaft 31 is mounted an eccentric 38, the strip 39 whereof is pivotally connected to a lever 40 mounted in the framing of the 45 engine and connected by a link 41 to said rod 27'. The shaft 31 is suitably driven from the crank shaft 2 or other suitable part, as by means of gearing indicated in dotted lines in Fig. 1, and in preferably the 50 ratio of two to one.

The exhaust valve 24 is provided with a transverse port 32 adapted, when the valve is lifted, to place the interior of the cylinder 55 6 into communication with the exhaust passage 33 leading to the exhaust pipe 34.

Preferably both the admission and the exhaust valves are arranged at the head end of the cylinder as shown.

In the position of the parts shown in Fig. 60 1, the admission valve 15 is about to open and the piston 5 is about to commence its downward or suction stroke. At about the completion of said suction stroke the valve 15 is depressed and closed by the continued 65 rotation of the cam shaft 21, and thereupon

the movement of the piston 5 is reversed and the compression stroke is effected. Upon the termination of the compression stroke ignition occurs and the downward or working stroke of the piston takes place. 70 Preferably at substantially the completion of the working stroke, though the timing of the parts may be varied to effect the best results, the exhaust valve 24 is opened and upon the exhaust stroke of the piston the 75 spent gases are expelled through the port 32 thereof. This completes one cycle of the engine.

The construction shown in Fig. 2 may differ only from that shown in Fig. 1 with 80 regard to the construction of either the admission or exhaust valves or both. In the construction shown in Fig. 1, said valves are preferably formed as cylindrical or otherwise suitably shaped plungers or plugs, each 85 having a transverse port therethrough. In the construction of the engine shown in Fig. 2 the admission and exhaust valves 35 and 36 are each shown as of inverted cup-like formation. Each of said valves is adapted 90 to seat and close against or within the valve seat 37, 37 and when lifted therefrom respectively permit the admission of the fuel mixture and the exhaust of the spent gases therefrom. That is to say, in the type of valve 95 shown in Fig. 2, the admission or exhaust occurs beneath the valve rather than through the same, although within the scope of my invention the admission and exhaust may be either above or below said valve or valves. 100

Any suitable means may be employed to reciprocate the valves 35, 36, and while I may employ substantially the construction represented in Fig. 1 for reciprocating the valves 15 and 24, I have herein represented 105 said valves 35 and 36 as provided with valve rods 29 threaded at their upper ends into said valves and at their lower ends suitably guided and provided with rolls 30 bearing upon cams 31 fast upon cam shafts 32 driven 110 from the crank shaft 2 by gearing or otherwise as indicated in dotted lines, and preferably in the ratio of two to one. The rolls 30 are held in contact with the cams 31 by coil springs 33 surrounding the valve rods 29, 115 and positioned between the framing of the engine and pins 33' upon said rods 29. In this manner the valves 35, 36 are positively opened and are closed by the action of the 120 springs 33.

Having thus described one illustrative embodiment of my invention, I desire it to be understood that although specific terms are employed, they are used in a generic and descriptive sense and not for purposes of 125 limitation, the scope of the invention being set forth in the following claims.

Claims:

1. An internal combustion engine comprising, in combination, a cylinder, a piston, 130

- crank shaft and connecting rod, valve chambers on the side of the cylinder, cylindrical piston slide valves working in said chambers, said valves including an admission 5 valve and an exhaust valve, lateral ports opening from said chambers into said cylinder, intake and exhaust passages aligned with said ports, said valves having straight openings therethrough constructed and arranged 10 to be in alinement with said ports and passages when the valves are open, and means for actuating said valves to open said ports in alternation each once for two revolutions of the engine shaft.
- 15 2. An internal combustion engine having a cylinder, a piston, crank shaft and connecting rod, transversely arranged admission and exhaust ports opening into said cylinder at the rear end thereof, a cylindrical piston
- slide valve at the side of the cylinder for controlling each port, said valves having diametrical ports therethrough adapted to register with said admission and exhaust ports respectively, means for actuating said exhaust valve to open the exhaust port once for each two revolutions of the crank shaft, and means alternately for actuating the admission valve to open the admission port also once for each two revolutions of the crank shaft. 20 25 30

In testimony whereof, I have signed my name to this specification, in the presence of two subscribing witnesses.
